[57] CLAIM

The ornamental design for a non-ice hockey puck, as shown and described.

DESCRIPTION

FIG. 1 is a perspective view showing the top and front side of the non-ice hockey puck showing my new design;

FIG. 2 is a top view thereof;

FIG. 3 is a right side view thereof, the left side view being identical;

FIG. 4 is a front side view thereof, the rear side view being identical;

FIG. 5 is a cross-sectional view taken along line 5—5 of FIG. 2;

FIG. 6 is a cross-sectional view taken along line 6—6 of FIG. 2;

FIG. 7 is a perspective view showing the top and front side of an alternate embodiment of the non-ice hockey puck of the present invention;

FIG. 8 is a top view of the puck of FIG. 7;

FIG. 9 is a right side view thereof, the left side view being identical;

FIG. 10 is a front side view thereof, the rear side view being identical;

FIG. 11 is a cross-sectional view taken along line 11—11 of FIG. 8; and,

FIG. 12 is a cross-sectional view taken along line 12—12 of FIG. 8.
